UNITED STATES PATENT OFFICE.

ARTHUR E. TAYLOR, OF ELYRIA, OHIO, ASSIGNOR OF ONE-HALF TO HEMAN ELY, OF ELYRIA, OHIO.

TACKLE-BLOCK.

SPECIFICATION forming part of Letters Patent No. 686,557, dated November 12, 1901.

Application filed February 18, 1901. Serial No. 47,738. (No model.)

To all whom it may concern:

Be it known that I, ARTHUR E. TAYLOR, a citizen of the United States, residing at Elyria, in the county of Lorain and State of Ohio, have 5 invented a certain new and useful Improvement in Tackle-Blocks, of which the following is a full, clear, and exact description, reference being had to the accompanying drawings.

The object of this invention is to provide a 10 very simple and efficient tackle-block—a block which may be made largely by stamping out of sheet metal and will be at once very cheap to produce and very strong and durable.

The invention consists in the arrangement 15 and construction of parts which contribute to the above end. It includes the utilization of a supporting-strap to lock the axle in place, broadly, and also more specifically, as shown; and it includes other features which contrib- 20 ute to the general result, all of which will be described, and definitely set out in the claims.

The drawings clearly disclose my invention.

The views on Sheet 1 show various embodiments of my tackle-block assembled. Figure 25 1 is a side elevation, Fig. 2 an edge elevation, and Fig. 3 a central section, of the tackle-block having two sheaves, which is the most common form. Fig. 4 is a central section of it with one sheave, and Fig. 5 a central section 30 with three sheaves. Fig. 6 is a fragmentary section of the axle, showing the interlocking strap. The remaining views, which are on Sheet 2, show separately all the parts necessary to compose the double tackle-block 35 shown in Figs. 1, 2, and 3. On this latter sheet Fig. 7 represents the frame, Figs. 8 and 9 the separators, Fig. 10 the main supporting-strap, and Fig. 11 the locking-strap, Fig. 12 the axle, Fig. 13 the retaining-bolt and 40 nut, Figs. 14 and 15 the sheaves, and Fig. 16 the becket. One of the purposes of this sheet of drawings is to clearly illustrate the large proportion of the tackle-block which may be stamped of sheet metal.

45 Referring to the parts by letters, A represents the frame, which is composed of the two outside plates a a' and the bridge-plate a^2 , connecting the two plates at the top. At its lower end the side plates a a' have the inwardly-projecting lips a^3 a^3 . The side plates 50 are dished or offset outward, as at a^4 , to pro-

vide for the reception of the supporting-strap and to stiffen these side plates. Through these portions a^4 is a hole a^5 to receive the ends of the axle. The construction of the 55 side plates of the frame is substantially the same whatever the number of sheaves used. The bridge-plate a^2 has different openings in it, according to the requirements, as will be explained. The axle (indicated by B) 60 occupies, as stated, the openings a^5 and loosely supports one or more sheaves C. The strain is taken directly from the sheaves and axle to the main supporting-strap D, which is of the general U shape and has through 65 its legs d the openings d' , which surround the axle, the strap occupying the space provided by the offset a^5 of the frame and passing through openings a^6 in the bridge.

The construction so far described is sub- 70 stantially the same in each form of the tackle-block.

Where two sheaves are used, I provide a pair of separators E, as shown detached in Figs. 8 and 9, which have openings e , through 75 which the axle may take, which have at their edges strengthening-flanges e' and at their upper edges lips e^2 and at their lower edges flanges or projections e^3 . The lips are adapted to take into openings, as a^7 , in the bridge- 80 plate a^2 of the frame, and the projections e^3 are adapted to abut against the side plates a a' just within the lips a^7 . When but two sheaves are used, the two separating-plates E E are back to back and have their flanges 85 e' abutting, as shown in Fig. 2.

When three sheaves are used, as shown in Fig. 5, there is placed between the two separators E a third separator F, the sides of which are formed just like the sides of the 90 separators E, but are connected together at their base by the cross-plate f , whereby a U shape is given to the intermediate separator. If four or more of the sheaves were used, the number of these intermediate separators 95 would be simply increased. The lips e^2 f at the upper ends of the separators take into openings in the bridge-plate a^2 , and the separators are held in place thereby and by the axle and by the bolt G, which extends through 100 holes a^8 in the side plates and through the holes e^4 in the separators and has on its end

a riveted head or nut g . Now between the abutting plates E or the plate E and the plate F , as the case may be, there is a space provided, owing to the flanges on these plates, 5 and this space is occupied by a second strap H . This strap has the two ends h connected at the upper end by the loop h' and having through the two legs the openings h^2 . In the form shown in Figs. 2, 3, and 11 these legs 10 are in contact with each other. In the form illustrated in Fig. 5 they are separated, but parallel with each other. In either event the two legs lie in the space between the separators. Now the holes h^2 in this strap H are of 15 the right size to allow the passage of the axle B ; but in use they are out of alignment longitudinally with the holes in the separators—that is to say, the distance between the holes h^2 and the holes h^3 , through which the bolt G 20 passes, is greater than the distance between the holes e and the holes e^4 or the holes a^5 and the holes a^8 . When the parts are assembled, the axle is passed through the wheels, 25 separators, and straps before the bolt G is in place, wherefore the holes h^2 may be caused to align with the others. Thereafter the strap H is drawn upward to bring the hole h^3 into 30 alignment with the holes e^4 a^8 , and this brings the lower edge of the holes h^2 into one or more notches b , formed in the lower side of the axle, and at the same time brings the strap H up against the strap D at the upper end, the holes being so positioned that this will take 35 place. When the strap H is brought up against the strap D , the axle is not only locked in place, but it bears on the lower surface of the hole h^2 as well as on the holes in the straps D , wherefore each of these straps helps carry the axle, and through it the weight, upon the 40 wheels. With the parts in this position the holes h^3 align with the holes e^4 and a^8 , and the bolt G is put in place and locked and there held, whereby the whole tackle-block is locked together.

45 When but one sheave is used, the straps D and H are consolidated into one strap, (indicated by J in Fig. 4.) The holes j , near the lower end of this strap, allow the passage of the axle B and then by elevation take into the 50 notches b therein, the strap being held in this locked position by the bolt G' passing through the frame A and the strap and held by a nut or rivet g' . This bolt serves the purpose of the bolt G in the former cases in holding the 55 strap so that its holes are out of alignment with the circumference of the axle. At the lower end the frame A is properly held by the bolt G^2 , passing through the distance-tube G^3 and locked by the nut or rivet g^2 .

60 A becket L is provided for the attachment of the end of the rope. This becket takes through an opening e^5 in one of the separator-lugs and loops around the bolt G .

In assembling the parts the separators are 65 first placed within the frame, the straps put in place with their openings aligned, the sheaves put between the separators, and the axle

shoved home. The axle is then turned, if necessary, as by a screw-driver in the slot b' in its end, to bring the notch or notches b onto the lower side, and the locking-strap is drawn up to lock the axle, whereupon the locking-bolt is shoved home and securely held.

Having described my invention, I claim—

1. A tackle-block having a frame, a supporting-strap engaging therewith and extending within the frame, an axle supported by said strap, a sheave on said axle, said axle presenting shoulders between the side plates of the frame and there being means between said side plates interlocking with said shoulders, substantially as described. 75

2. In a tackle-block, in combination, a sheave, an axle for supporting the same, and having one or more notches in it, a strap having openings for the reception of said axle, said strap being adapted to occupy said notches, and means for holding the strap in the notches whereby the axle is locked, substantially as described. 85 90

3. In a tackle-block, the combination of a sheave, an axle therefor, a frame, and a strap which both locks the axle and supports the same, substantially as described.

4. In a tackle-block, in combination, an axle, sheaves supported thereby, a pair of straps for supporting said axle one of said straps when in the supporting position locking with said axle, said locking-strap nesting within the other strap and moving toward it to so lock the axle, substantially as described. 95 100

5. In a tackle-block, a sheave, an axle supporting the same, said axle having one or more notches intermediate of its ends, a frame having side plates with aligned openings which the ends of said axle occupy, a strap having openings through which said axle may be passed, and means for holding said strap with its openings out of alignment with the openings through the frame whereby the axle is locked in place, substantially as described. 105 110

6. In a tackle-block, in combination, an integral sheet-metal frame consisting of a top plate and a pair of side plates bent therefrom, there being a pair of openings through the top plate adjacent to the side plates, a strap extending through such openings and lying against the side plates, there being holes in said strap and holes in the side plates, an axle occupying said holes, and a wheel supported by said axle, substantially as described. 115 120

7. In a tackle-block, the combination of an integral sheet-metal frame consisting of a top plate and a pair of side plates extending therefrom, a plurality of sheet-metal separator-plates intermediate of the side plates, said separator-plates engaging at their upper ends the top plate and being bent outwardly at their lower ends whereby they integrally engage the side plates, substantially as described. 125 130

8. In a tackle-block, the combination of a frame including a pair of side plates, a plurality of separator-plates rigidly held inter-

mediately of the side plates, an axle, a locking-strap extending between said separator-plates and adapted to engage said axle, and sheaves on said axle, substantially as described.

9. In a tackle-block, the combination of a frame including a pair of side plates, a plurality of separator-plates intermediate of the side plates and suitably held distant therefrom, an axle, a locking-strap extending between said separator-plates and adapted to engage said axle, and a bolt clamping said side plates and separator-plates and holding said strap in locked position, substantially as described.

10. In a tackle-block, a frame including a pair of side plates, two or more separator-plates intermediate of the side plates and having axle-openings in them, combined with a locking-strap occupying the space between adjacent separator-plates and having an opening adapted to align with the openings through the separator-plates, an axle adapted to occupy such openings, said axle having one or more notches which said locking-strap may occupy, and means for holding said strap in position so occupying said notches, substantially as described.

11. In a tackle-block, the combination of a frame having a pair of parallel side plates, a main strap lying along side plates, there being holes through the side plates and through the main strap for the reception of an axle, a locking-strap having one or more holes for the reception of the axle and adapted when shifted to occupy one or more corresponding notches in the axle, and a bolt passing through said side plates and through said locking-strap, and operating to hold said strap in said locked position, substantially as described.

12. In a tackle-block, the combination of a frame having a pair of side plates and a connecting top plate, intermediate separators between said side plates, said separators engaging the top plate and being held parallel with the side plates, said separating-plates having abutting flanged edges whereby a space is provided between them, a locking-strap adapted to occupy such space, and an axle extending across said separators and engaged by said locking-strap, substantially as described.

13. A tackle-block adapted to be made largely of sheet metal including a frame having side plates and a bridge-plate, a pair of separating-plates having lips at their upper ends and outwardly-turned projections at their lower ends, said lips engaging one or more openings in said bridge-plate and said projections engaging said side plates, and a bolt passing through the side plates and through the separating-plates for clamping the same together, an axle occupying aligned

holes in said side plates and separating-plates, and sheaves on said axle, substantially as described.

65

14. A tackle-block adapted to be made largely of sheet metal including a frame having side plates, a pair of separating-plates having outwardly-turned projections at their lower ends, said projections engaging said side plates, and a bolt passing through the side plates and through the separating-plates for clamping the same together, an axle occupying aligned holes in said side plates and separating-plates, and sheaves on said axle, 75 combined with a locking-strap occupying the space between the separating-plates and engaging said holes, substantially as described.

15. In a tackle-block, in combination, a frame made of sheet metal and consisting of 80 a pair of side plates, and a bridge-plate at the upper end thereof, said side plates having inwardly-projecting wings at their lower ends, a pair of sheet-metal separator-plates between said side plates having lips at their upper ends extending into an opening in said bridge-plate and having lugs at their lower ends engaging said side plates in proximity to said lips, a bolt near the lower end of said tackle-block passing through said side plates 90 and separating-plates and clamping the same together, an axle occupying aligned openings in the separating-plates and side plates, and sheaves on said axle, substantially as described.

95

16. In a tackle-block, in combination, a frame made of sheet metal and consisting of a pair of side plates and a bridge-plate at the upper end thereof, said side plates having inwardly-projecting wings at their lower ends, 100 a pair of sheet-metal separator-plates between said side plates having lips at their upper ends extending into an opening in said bridge-plate and having lugs at their lower ends engaging said side plates in proximity to said lips, a bolt near the lower end of said tackle-block passing through said side plates and separating-plates and clamping the same together, an axle occupying aligned openings in the separating-plates and side plates, 110 sheaves on said axle, said side plates being offset or dished outward, there being openings through the bridge-plate communicating with such dished portion, and a strap occupying such dished portion and having openings for the reception of said axle, substantially as described.

In testimony whereof I hereunto affix my signature in the presence of two witnesses.

ARTHUR E. TAYLOR.
